UNITED STATES PATENT OFFICE.

AARON SAWYER NICHOLS, OF BOSTON, MASSACHUSETTS.

VENEER-DRIER.

SPECIFICATION forming part of Letters Patent No. 767,654, dated August 16, 1904.

Application filed May 25, 1904. Serial No. 209,640. (No model.)

To all whom it may concern:

Be it known that I, AARON SAWYER NICHOLS, a citizen of the United States, residing in Boston, in the county of Suffolk and State of Massachusetts, have invented a new and useful Improvement in Veneer-Driers, of which the following is a specification.

In the patent granted to me on January 19, 1904, No. 750,058, I show the vertical platens of a veneer-drier provided with horizontal pins adapted to support narrow veneers at levels above the bottoms of the platens, the pins projecting from the face of one platen into registering openings provided in the face of the opposing and adjacent platen. The present invention is a modification of the construction shown in said patent and is intended to accomplish the same result—namely, that of increasing the capacity of the driers in operating upon narrow veneers by providing means for supporting the narrow veneers between the upper portions of the platen-faces.

The invention consists in the novel features hereinafter described.

In the accompanying drawings, Figure 1 is a front elevation of a veneer-drier provided with my present invention. Fig. 2 is a face view of one of the platens. Fig. 3 is a partial vertical section of the drier.

In said drawings, 5 5 represent a series of platens supported at their ends by swinging rods 6 and connected by the pipes 7 to a suitable header or source of steam-supply. At each side of the series of platens is a toggle 8, by the lengthening of which the platens are forced together, so as to compress the veneers between them, and by the shortening of which the platens are drawn apart to allow the escape of the vaporized moisture and the insertion and removal of the stock, the toggles being operated by any suitable mechanism through the medium of rods 9. Instead of short pins fixedly secured in the platen after the manner shown in my said patent I now use rods 10 of sufficient length to extend through the entire series or through a portion of the series of platens, and the openings 11

in which the rods are inserted extend transversely through the platens from face to face thereof and are wholly unobstructed, so that 50 the rods can be put in or taken out whenever desired. The entire series of platens are preferably provided with the openings 11, and such openings are in alinement, and the rods fit them loosely, so that the putting in and 55 taking out of the rods is rendered easy. The openings are provided in such numbers and in such locations as desired in the platens, and the rods are taken out whenever wide veneers are to be dried. The rods are adapted to support the narrow veneers in the same manner as do the pins of my patent, and I have shown in Fig. 3 veneers 12 as resting upon them. The openings in the platens are preferably 60 lined by short tubes or bushings 13, substantially as in the patent. The supporting-rods should be of suitable length, so that the platens in which they are inserted will not be drawn off of them when the platens are opened, and they should fit loosely in the 65 openings, so as not to create unnecessary friction upon the platens when the latter are opened and closed.

By this invention I am able to dry two or more courses of veneers between adjacent 75 platens simultaneously without increasing the size of the platens or the amount of steam required, and the platens are held apart by the stock both at the top and bottom, and as the supporting-rods are positioned variously at 80 different times there is but little appreciable wear upon them. The rods 10 need not extend through the entire series of platens and, in fact, need be passed through only so many of them as are needed for the narrow stock, 85 so that wide stock may be dried at the same time between the platens through which the rods do not extend.

I claim—

1. The veneer-drier having vertical platens 90 provided with registering openings, in combination with loose supporting-rods inserted in said openings.

2. The series of vertical platens having

transverse openings therethrough arranged in alinement, in combination with loose rods for supporting veneers passed through said openings.

5 3. The veneer-drier having a series of vertical platens provided with unobstructed openings extending entirely through the same from face to face, said openings being arranged in

alinement, in combination with loose rods inserted in the openings and acting to support the veneers.

AARON SAWYER NICHOLS.
